UNITED STATES PATENT OFFICE.

PETER C. PINKERTON, OF INDIANAPOLIS, INDIANA, ASSIGNOR OF ONE-HALF TO
WALTER J. BAKER, OF INDIANAPOLIS, INDIANA.

HOOD AND IGNITION LOCK FOR AUTOMOBILES.

Application filed May 13, 1924. Serial No. 713,049.

To all whom it may concern:

Be it known that I, PETER C. PINKERTON, a citizen of the United States, residing at Indianapolis, in the county of Marion and

5 State of Indiana, have invented certain new and useful Improvements in Hood and Ignition Locks for Automobiles, of which the following is a specification.

My said invention relates to a hood and 10 ignition lock for automobiles and it is an object of the same to provide a device of this character which shall provide an efficient lock for the hood as well as for the ignition and thus provide means for safeguarding automobiles from theft.

Further objects are to provide a device which is not likely to operate automatically to shut off the current while the car is running at a high speed, thereby endangering 20 the car and its occupants; which shall be purely mechanical and not automatic; which shall not be troublesome in wet weather because of batteries and magnets in addition to those ordinarily found in an internal combustion engine and which shall be capable 25 of attachment to any car with ease and facility.

Referring to the accompanying drawing which is made a part hereof and on which 30 similar reference characters indicate similar parts,

Figure 1, is a side elevation illustrating the application of my improved device to an automobile,

35 Figure 2, an enlarged fragmentary side elevation,

Figure 3, a vertical section on line 3—3 of Figure 1,

Figure 4, a detail of a contact support 40 shown in Figure 3, and

Figure 5, a fragmentary view of a portion of the hood and a part attached thereto.

In the drawing reference character 10 indicates a part of the frame of an automobile 45 on which is located a hood 11 of ordinary type. Underneath the hood is a coil box 12 connected by a wire 13 to a timer 14, all of these parts being of ordinary type and familiar to those skilled in the art.

50 The hood is provided with latches 15 at each side as usual, the device constituting my invention being preferably substituted for the front latch at the left-hand side. The body 16 of the latch of my device is provided with horns 17 or any other con-

venient means for lifting said body which is here shown as hollow and enclosing the spring 17^a surrounding an anchor bolt 18 having a nut 19 at its upper end. A nut 20 has threaded engagement with the hollow 60 body at its lower end, said nut having an opening loosely surrounding the anchor 18. The nut 20 is held against rotation by one or more pins 21 passing through the wall of body 16 into holes in the nut. 65

At its lower end, the anchor has lateral projections 22 resting in a downwardly opening slot of a block 23. This block is secured to the frame member 10 by means of bolts 24 passing upward through holes in 70 the frame member and having threaded engagement with holes in the block. The body 16 has a catch 25 engaging in an aperture 26 formed in a relatively heavy plate 27 bolted to the side of the hood said aperture also 75 extending through said side.

The body 16 is provided adjacent its upper end with a lock 28 which is of the Yale type and is provided with a rotary bolt 29 having an arm 30 projecting laterally for engagement with a terminal in the form of a screw 31 supported on a strip 32 of vulcanized fiber or the like attached to the upper end of a resilient standard 33 which passes through an opening in the frame and has a 85 bent portion 34 underneath the frame secured thereto by screws or other convenient means. A key 35 serves to rotate the bolt which projects through an aperture at 36 in the plate 27 said aperture also extending 90 through the side of the hood.

In the operation of my device when the bolt is in the dotted line position illustrated in Figure 3 and in light lines in Figure 4 the end of the bolt projects slightly over 95 a shoulder formed by the offset upper portion 33' of the standard 33 and alongside the fiber strip 32 to prevent accidental contact of the bolt with screw 31. If desired a casing about the bolt may project at this 100 point to aid in preventing accidental engagement between the bolt and the screw 31 which through a wire 37 is connected to the wire 13 between the coil box 12 and the timer 14 in a manner to ground the circuit. 105

At this time the catch 25 acts to hold the hood down but by raising the body 16 this catch may be disengaged and the catch formed by the lateral arm on the bolt 29 may also be retracted freely through the 110

upper opening in the hood. When it is desired to lock the hood and the ignition key 35 is inserted in the plug and the bolt is turned into the full line position of 5 Figure 3 which is the heavy line position of Figure 4, the arm 30 being somewhat beveled to force the standard 33 slightly back so that the arm can come into engagement with the screw 31 and the arm resting 10 at its rear side against the hood. This grounds the circuit through the timer and at the same time brings the catch 30 into the dotted line position of Figure 5 where it presses firmly against the hood to prevent 15 withdrawal of the latch from the hood and so prevent raising of the hood.

Various modifications of my device will be obvious to those skilled in the art and therefore I do not limit myself to what is 20 shown in the drawings and described in the specification, but only as indicated in the appended claims.

Having thus fully described my said invention, what I claim as new and desire to 25 secure by Letters Patent is:

1. A hood and ignition lock for automobiles comprising a latch for the hood, a bolt carried by the latch having an end projecting through an aperture in the hood, a laterally projecting arm on the bolt adapted in 30 one position to prevent withdrawal of the latch, and a contact located underneath the hood in position to cooperate with said laterally projecting arm to ground the ignition circuit, substantially as set forth.

2. A hood and ignition lock for automobiles comprising a latch for the hood, a bolt carried by the latch having an end projecting through an aperture in the hood, a laterally projecting arm on the bolt adapted in 40 one position to prevent withdrawal of the latch, a resilient standard under the hood, and a contact on said standard adapted to cooperate with said lateral arm to ground the motor circuit, substantially as set forth.

3. A hood and ignition lock for automobiles comprising a hollow body, a lateral arm adapted to engage an aperture in the hood, a block on the frame of the machine, 50 an anchor bolt pivotally connected to said block and projecting into the hollow body, a spring surrounding said anchor bolt, and means at the ends of the spring for confin-

ing it within the hollow body, said means being connected respectively to the body and 55 the bolt, substantially as set forth.

4. A hood and ignition lock for automobiles comprising a block having a downwardly opening slot, bolts projecting upward through a part of the frame into threaded engagement with said block, an anchor bolt having laterally projecting arms in said slot and an upwardly projecting portion, a latch resiliently connected to said portion, and a bolt on said latch for locking 60 the latch in engagement with the automobile hood, substantially as set forth.

5. In a hood and ignition lock for automobiles, a pivoted latch, a hook on the latch, 70 resilient means for holding the hook in latching position relative to the hood, and a bolt on said latch adapted to have locking relation with the hood, substantially as set forth.

6. In a hood and ignition lock for automobiles, a pivoted latch, a catch on the latch, resilient means for holding the catch in latching position relative to the hood, and a bolt on said latch adapted to have locking 75 relation with the hood said bolt also cooperating with a contact to ground the ignition circuit, substantially as set forth.

7. In an ignition lock for automobiles, a standard under the hood having an offset portion at its upper end, a fiber strip projecting upward from said offset part, a contact on the fiber strip, and a rotary contact adapted to engage the first contact for grounding the circuit, said rotary contact 85 normally projecting over the shoulder formed by the offset, substantially as set forth.

8. In an ignition lock for automobiles, a standard under the hood having an offset portion at its upper end, a fiber strip projecting upward from said offset part, a contact on the fiber strip, and a rotary contact adapted to engage the first contact for grounding the circuit, substantially as set forth.

In witness whereof, I have hereunto set my hand and seal at Indianapolis, Indiana this 9th day of May, A. D. nineteen hundred and twenty-four.

PETER C. PINKERTON. [L.S.]
